UNITED STATES PATENT OFFICE.

GEORGE W. GWINN, OF NEW YORK, N. Y., ASSIGNOR TO AUTOMATIC PACKING & LABELING COMPANY, OF DURHAM, NORTH CAROLINA, A CORPORATION OF NORTH CAROLINA.

MACHINE FOR APPLYING STAMPS TO CANS OR OTHER CONTAINERS.

1,315,956.

Specification of Letters Patent. Patented Sept. 16, 1919.

Application filed April 20, 1916. Serial No. 92,485.

To all whom it may concern:

Be it known that I, GEORGE W. GWINN, a citizen of the United States, residing at New York, in the county of New York and 5 State of New York, have invented a certain new and useful Improvement in Machines for Applying Stamps to Cans or other Containers, of which the following is a specification.

10 My present invention pertains to an improved mechanism for applying stamps or the like to cans or similar containers.

One embodiment of my invention is disclosed in the annexed drawings, wherein:

15 Figure 1 is a sectional elevation of the mechanism;

Fig. 2 a top plan view;

Fig. 3 a vertical sectional view on the line 3—3 of Fig. 1;

20 Fig. 4 a sectional elevation, similar to Fig. 1, the parts being shown on an enlarged scale and showing a can which has just been passed through the stamp applying mechanism and having a stamp positioned thereon;

25 Fig. 5 a horizontal section on the line 5—5 of Fig. 1 (enlarged);

Fig. 6 a detail view illustrating the presser foot or finger employed to hold the stamp as the can with the stamp thereon is 30 passed between the brushes or wipers employed to wipe the ends of the stamp down against the sides of the can;

Fig. 7 a detail sectional view on the line 7—7 of Fig. 4;

35 Fig. 8 an elevation of the driving mechanism employed to actuate the can retaining mechanism;

Fig. 9 a side elevation, parts being broken away, of the stamp feeding mechanism;

40 Fig. 10 a detail sectional elevation of the paste applying mechanism;

Fig. 11 a detail perspective view of one of the can holders; and

45 Fig. 12 a vertical sectional view on the line 12—12 of Fig. 4.

Tobacco is to a very large extent now being packed in tin cans having hinged lids and it is of course necessary to place revenue stamps on said cans, and the present invention pertains to an improved mechanism for effecting such operation. It is to be understood, however, that in its broader aspect

the mechanism, or certain parts thereof, may be employed to place and secure stamps (which term is employed in a generic sense 55 and is to be treated as the equivalent of a label, sealing strip or the like) on containers or packages other than cans.

The structure may be said in general terms to comprise stamp applying mechanism, including stamp presenting and wiping devices; means for holding the can after the stamp is positioned thereon, including a conveyor or the like, and associated stamp pressing mechanism adapted to hold and 60 press the stamp against the can; means, where the machine is automatic or the stamping mechanism is associated with can filling or other mechanisms, for presenting the cans to the stamping mechanism; and lid 65 closing means where such can presenting means is present.

In the form shown all such devices or mechanisms are employed.

Referring to the drawings 1 denotes a 75 table, 2 a turret, having pockets 3 therein for the reception of cans 4, having hinged lids 5. The cans are designed to be placed in the pockets by hand, or by any suitable transfer mechanism (not shown) where a 80 weighing and packing mechanism is utilized. A step by step motion is imparted to the turret through any suitable mechanism, that shown comprising a pocketed wheel 6 secured to the turret supporting shaft 7 with 85 which wheel co-operates a lever or arm 8 carrying a bowl 9. Constant rotation is imparted to the shaft carrying lever 8 through gears 10 and 11, the latter being secured upon a counter shaft 12 which carries a second gear 13 meshing with a gear 14 secured upon a power or driven shaft 15.

The cans as they are carried around by the turret into position over an opening 16 in the table are held in the pockets by guide 95 rails 17 and 18 and prior to their reaching said opening the lids 5 are closed by a suitable mechanism, that shown being substantially the same as that set forth and claimed in my copending application filed on or 100 about December 1st, 1914, Serial No. 875,016, now Patent No. 1,276,523, dated August 20, 1918.

In general it may be said to comprise a

cam shaped member 17^a, Fig. 5, which underlies the can top 5 and acts, as the can is advanced by the turret, to turn the lid or top upwardly and over and then down 5 into closed position, a roller 18^a being located adjacent the end of the cam and acting on the closed lid to force the same to its fully closed position.

When the can comes to rest over the opening 16 with its lid closed down, it is then moved upwardly into contact with a stamp to which paste has been applied and the stamp is clamped or pressed against the lid and the can and stamp carried up between 10 devices which act to wipe its ends down and against the sides of the can.

Secured to a bracket 19, Fig. 3, in which one end of shaft 12 is supported, is a vertically disposed guide 20 upon which is mounted a slide 21, said slide having secured to it a link 22 to which in turn is pivotally secured a lever 23 (Fig. 1) fulcrumed on a rod 24 (Fig. 2).

A roller 25 mounted on the lever works 25 in a cam groove 26 formed in one face of a cam 27 secured to shaft 15 and through this arrangement the slide 21 is periodically raised and lowered. Said slide has secured to it two vertically disposed rods 28 and 29, 30 the former being provided at its upper end with a plate 30 adapted to contact with the bottom of the overlying can and to elevate or carry the same upwardly into contact with the stamp and between the two oppositely disposed and vertically arranged stationary brushes 31 and 32. Rod 29 is adapted to elevate a slide 35 which carries the finger 33, which as the can begins its 35 upward movement comes to rest upon the 40 stamp, indicated by 34.

Presser finger 33 is pivotally mounted on the slide 35, which is slidably mounted upon a fixed guide-way 36 secured to a bracket 37 fastened or supported by a cross bar 38 45 which in turn is secured to posts 39 (Fig. 3), extending upwardly from the bed or table 1. A spring 40 tends to draw the outer end of the finger downwardly, its descent being limited by the stop screw 41. 50 Slide 35 is free to move or gravitate upon the guide 36, and to limit its downward movement it is provided with a lug 42 in which is preferably seated a cushion adapted when the slide is in its lowest position 55 to contact with an adjustable set screw 43 mounted in a lug extending outwardly from the guide or slide-way 36. Said screw is so adjusted that when the slide is in its lowest position the end of the presser finger 60 will be held above the stamp which is drawn across the upward path of movement of the can at a point slightly above said top as will presently appear.

A second stop screw 44 is located adjacent the upper end of guide-way 36 and is

adapted to contact with the rear end of finger 33 and rock the same from the position shown in Figs. 1 and 6 to that indicated in Fig. 4 when the slide 35 is fully elevated, thus withdrawing the finger from the stamp against which it came into contact shortly after the can began its upward movement. 70

Normally the slide travels up with the can, being actuated by the rod 29 which contacts screw 45^a, finger 33 maintaining its pressure on the stamp. When, however, the slide 35 nears its limit of upward movement, the rear end of the pivoted finger 33 contacts with the adjustable screw 44, and 75 the finger is rocked, bringing it to the position shown in Fig. 4, entirely free of the can and the then adherent stamp. 80

To maintain the can in its vertical position after it is removed from the turret 85 suitable guides, forming what may be termed a guide-way, are provided. To one side of the turret, adjacent the opening 16 there is secured a block or casting 45 (see 90 Figs. 3 and 4) upon which are secured two U-shaped guide members 46 and 47 and extending upwardly and between them is a guide plate 48 preferably formed of spring metal. Said members extend upwardly to a point where the stamp is drawn in a horizontal direction across the top of the can, and above and to the rear secured to the cross bar 38 are two guides 49 and 50 which align with guides 47 and 48. Another pair of guides 51 and 52 are arranged 100 opposite said last named guides and serve with the latter to hold the can against tilting as it is pushed upwardly between the brushes 31 and 32 which wipe the ends of the stamp against the sides of the cover and 105 body.

Any form of stamp presenting mechanism may be employed which will place the stamps over the cans, one at a time.

Secured to shaft 12 is a cam 53 and a lever 110 having three arms 54, 55 and 56 is fulcrumed at 57 on the bracket 19. A link 58 extending from the upper end of arm 55 is connected to a slide 59 mounted to reciprocate upon a bar or slide way 60 secured to 115 columns 39. Said slide (see Fig. 9) carries a pair of pincers comprising a fixed jaw 61 and a pivoted jaw 62, the latter being provided with a downward extension 63 adapted, when the pincers near their limit of movement in the placement of a stamp, to contact with a fixed block 64 and to rock the upper jaw, or in other words to open the pincers against the stress of a spring 65 which tends 120 normally to hold the jaws closed. A latch 125 66 is drawn in by a spring 67 beneath a projection on said movable jaw when the parts reach the position shown in Fig. 9, at which time a stamp has been drawn through and across the can guide way. When moved 130

to the left (see Fig. 3) the lower end of the latch 66 contacts with a block 68 which releases the jaw 62, permitting it to grasp the lowermost protruding stamp 34 in the 5 stamp holder or box 69.

Such protrusion is brought about through the agency of a pusher 70 mounted on an adjustable stem 71 carried in one end of a rocker arm 72 secured to a shaft 73. Said 10 shaft is mounted in a slide 73^a mounted on guide way 60 and carries a lever or finger 74, the upper end of which lies between two fixed stops A and B, carried by the slide. The upper end of said finger stands in line 15 with a rod 75 adjustably mounted in a block 76 secured to a rod or bar 77 which is secured to and extends outwardly from slide 59.

When, as shown in Fig. 9, the pincers are moved to the right and have released the 20 stamp, the rod 75 will have come into contact with the lever 74 and will throw the pusher 70 against the lowermost stamp, the lever 74 coming to rest against the fixed stop B 25 when, upon further movement, the lever 74 and slide 73^a, together with the arm 72 and pusher 70, will move to the right as one and protrude the stamp, as shown in Fig. 9. At the beginning of the return movement of 30 the pincers to the left the rod 75 will move out of contact with lever 74, and the pusher 70 will drop away from the stamp, the lever 74 swinging to the left and coming into contact with the fixed stop A. As the pincers 35 near their limit of movement to the left, a finger or projection 78, carried by the pincer slide 59, will hit the lever 74 and throw it against the stop A, provided it has not gravitated against said stop, and thus move 40 the slide 73^a to the left into place where the pusher will again be in position to act upon the stamp which is subsequently exposed upon withdrawal of the then-protruded stamp.

45 Rod 77 is provided with a rack upon its under face, said rack meshing with a gear 79 which in turn meshes with a gear 80, Fig. 10. Gear 80 is mounted loosely on its supporting shaft and imparts motion there- 50 to in one direction only, through a clutch mechanism, indicated generally by 81, Fig. 10. A gear 82 secured to the opposite end of the shaft meshes with a gear 83 and the shaft which carries this gear likewise car- 55 ries paste applying rolls 84, and a gear 85, the latter meshing with a gear 86 mounted on a shaft which carries the paste feeding roll 87. The latter is submerged in the paste receptacle 88. Through the 60 clutch mechanism the paste rolls are driven as the stamp is advanced over the same and remain idle upon retrograde movement of the pincers.

The parts are so timed that just prior to 65 the ascent of the push rod 28 the stamp

positioning mechanism will operate to draw a stamp out and place it over the can, the pincers remaining at the right, Fig. 9, until the rod 28 is moved upwardly, carrying the can with it and again descends. Said 70 rod comes to rest when it reaches its highest elevation so that the stamped can may be moved laterally into operative relation with suitable devices for applying a continued pressure to the stamps and to hold them until they are dry. 75

The can when it is fully elevated stands to one side of bar 38 upon which, with its upper face in line with the bottom of the can, is a block or plate 88^a, Fig. 4, and suitable mechanism is employed to shift the can laterally over this plate and onto one member of a can clamping mechanism, later described. 80

The shifting mechanism comprises an L-shaped casting 89, best shown in Fig. 2, to the forward end of which is secured a vertically-disposed bar or plate 90. The rear end of the casting 89 is secured to a slide 91 which is mounted in a slide way formed 90 in a bracket 92, Figs. 2 and 3, a second vertically disposed push plate 93 being secured upon the outer end of the slide in vertical alinement with plate 90. Said shifting mechanism or bunter, as it may be termed, 95 is actuated through the agency of a bell crank lever 94, Fig. 1, a link or draw rod 95 being interposed between the upper end of the lever and the slide 91, while the lower arm of the lever is provided with a bowl 100 96 which works in a cam groove 97 of cam 27.

The can holding and stamp clamping mechanism, adapted to fully set and hold the stamps in contact with the cans until 105 the paste is dry, may take various forms, and one which I have found highly efficient is disclosed herein. It may be said to comprise a pair of endless chains carrying a series of can grasping carriers with which 110 are associated brushes to act upon the ends of the stamps combined with means for periodically advancing the chains step by step, and means for closing the clamps upon the cans and thereafter opening the same to discharge the cans. 115

Secured to and extending upwardly and rearwardly from cross bar 38 is a pair of brackets 98 and 99, Figs. 2 and 7, in which is journaled a shaft 100 and secured to the 120 shaft is a double sprocket wheel 101. A second shaft 102, Fig. 1, is sustained in a suitable support 103 and carries a spool like wheel 104, the flanges of which fit between the links 105 of the endless chains of the 125 carrier, the links being arranged in oppositely disposed pairs. Said links, see Fig. 11, are connected by cross pins 106 to the body member 107 of the can clamping device or carrier, said member being provided 130

at one end with an upstanding member or element 108.

Rollers 109 are also mounted on the pins and bear upon oppositely disposed upper 5 and lower guide bars or tracks 110 and 111, see Fig. 12, said tracks being supported by castings 112, see Fig. 4, which in turn are secured to intermediate supporting bars 113 attached at one end to brackets 98 and 10 99 and their opposite end to the support 103.

As will be noted upon reference to Fig. 11, one end of body member 107 is recessed and is adapted to receive a block 114, provided with a downwardly extending bifurcated lug 115, having an eye through which the adjacent pin 106 freely passes. From one member of said lug an arm or lever 116 projects, and a roller 117 is mounted on one side thereof. A spring 118 fastened at one end to pin 106 next adjacent the member 108 is connected at its opposite end to a screw 118^a secured in block 114 and tends under normal conditions to draw the block 114 to the fixed member 108. Said 25 block 114 carries a presser plate 119 which when the block is rocked inwardly by the spring will press against the stamp upon the can, if one be at rest upon the body 107, the bottom of the can at such time taking 30 against the foot piece or element 108.

A cam 120, see Figs. 1 and 4, extends forwardly between the sprockets 101, and stands in line with and bears against the roller 117 when the holders stand in the position shown in Fig. 4 thereby tilting or rocking the member 114 and opening the holder or carrier so that a can may be moved into the then horizontally disposed shoe or element 108 by the bunter before described. 35 The holders are successively opened as they are advanced and as they come to rest are each charged with a stamped can. As the chain moves, the roller 117 moves away from the cam and the spring serves to force the member 119 against the stamp and the latter against the can top. As the carrier or chain is advanced the cans are carried between a plurality of oppositely disposed brushes 121 supported by brackets 122 which brushes 40 tend to wipe and hold the ends of the stamps against the sides of the cans. Suitable heating or drying devices, such as electric heaters, hot air blasts, well understood in the art 45 may also be employed if desired.

The cans are finally discharged at a suitable point along the lower run of the carrier through the action of a cam 123 which opens the holder as shown in Fig. 4, by acting on the roller 117.

The carrier has a step by step motion imparted thereto by the mechanism best shown in Figs. 3, 4, 7 and 8.

Secured upon the outer end of shaft 100, Fig. 7, is a toothed wheel or ratchet 124, and 65 journaled on the shaft immediately adjacent

thereto is a sector gear 125, an arm 126 extending outwardly therefrom and carrying a pawl 127, the latter being held in co-operative relation with the ratchet by a spring 128. An oscillating motion is imparted to 70 the sector gear by means of a rack 129, which derives its motion from cam 53 and arm 56, said arm being connected by a link 130 to a lever 131 secured to a shaft 132 mounted in a bracket 133, the opposite end 75 of said shaft carrying a lever 134, which in turn is connected by a shear or safety pin to a link or bar 135, the upper end of which is connected to the lower end of rack 129.

These connections impart a step by step 80 movement to the carrier, the pawl 127 riding freely back over the ratchet wheel 124. Cam 53 is also formed with a dwell so that when the bunter is moving a can laterally and then retreating the carrier is at rest with 85 one of the can clamping devices open and in position to receive a stamped can as indicated in Figs. 1 and 4.

As above indicated, the mechanism herein set forth may be directly associated and 90 work in conjunction with a weighing and packing mechanism, such for instance as that shown in my co-pending application filed on or about the 29th day of December, 1914, Serial No. 879,565, now Patent No. 95 1,221,313, dated April 4, 1917, to which reference is hereby made.

It is of course conceivable that instead of employing a carrier having separate and independent carriers for each of the stamped 100 cans, as above set forth, other means may be employed to take care of the cans immediately the stamps are applied to hold the stamps in place until they are dry, as for instance a runway into which the cans 105 are discharged and passed, and held in proper position with relation to each other and to suitable devices, as brushes, and the like, which effect a proper adhesion and drying of the stamps upon the cans. 110

Having thus described my invention, what I claim is:—

1. In a machine for stamping cans, the combination of means for placing a stamp across the lid of the can with the ends of 115 the stamp protruding beyond the lid; a spring actuated member for pressing and holding the central portion of the stamp upon the lid; means acting to wipe the ends of the stamp against the sides of the can 120 while the stamp is thus held; means for positively relieving the spring actuated members from such pressing relation and means acting to move the can endwise into operative relation with the stamp wiping 125 means.

2. In a machine for stamping cans, the combination of a way through which the cans may be moved; means for advancing the cans therethrough; brushes located on 130

opposite sides of the way and operative on the ends of the stamps; spring actuated means for pressing and holding the stamp upon the lid while passing between the 5 brushes; and means for positively releasing said spring actuated means.

3. In a machine for stamping cans, the combination of a way through which the cans may be moved; means for advancing 10 the cans therethrough; brushes located on opposite sides of the way and operative on the ends of the stamps; and means for receiving and clamping the stamped cans one by one and thereby maintaining the stamps 15 in close relation to the cans until the adhesive employed to secure the stamp is dry.

4. In a machine for stamping cans, the combination of a way through which the cans may be moved; means for advancing 20 the cans therethrough; means for positioning a stamp over each can lid as the cans are advanced; means for pressing the central portion of the stamp on the lid; means for drawing or forcing the ends of the 25 stamp down upon the ends of the lid and can body; and means for receiving the stamped can, clamping the same and simultaneously exerting pressure upon the central portion of the stamp, and to thus hold 30 it while it dries.

5. In a machine for stamping cans, the combination of a way through which the cans may be moved; means for advancing the cans therethrough; means for positioning a stamp over each can; means for holding 35 the stamp upon the top of the lid as the can is moved through the way; brushes located upon opposite sides of the way to wipe the ends of the stamp down against 40 the can; means for releasing the stamp holding means; means for receiving the stamped cans and retaining the stamps under pressure until the adhesive employed is dry; and means for transferring the 45 stamped can to said receiving means.

6. In a machine for stamping cans, the combination of can presenting means; lid closing mechanism; means for actuating the can presenting means to thereby bring the 50 cans into operative relation to said closing mechanism and associated stamp applying means.

7. In a machine for stamping cans, the combination of a pocketed turret adapted to 55 hold and advance cans; lid closing mechanism associated therewith; stamp applying means; and means for receiving the stamped cans and holding the stamps under pressure thereon until the stamps are dry.

8. In a machine for stamping cans, the combination of a pocketed turret, adapted to hold and advance cans having hinged lids; a lid turning and closing mechanism associated therewith; a guide or way for 65 the cans terminating at one end adjacent to

the turret; means for drawing a stamp across said way; means for removing the cans from the turret and traversing the same through the way; and means associated with said way to wipe or draw the stamp 70 upon the lid and sides of the can.

9. In a machine for stamping cans, the combination of can presenting means; a guideway for the cans; means for advancing a stamp across said way; brushes located 75 adjacent the sides of the way; a finger extending into the way and pressing the stamp upon the lid of the can; means for moving the can through the guideway and between the brushes; and means for releasing the finger when the can reaches its limit 80 of movement through said way.

10. In a machine for stamping cans, the combination of a guideway for the cans to be stamped; means for drawing a stamp across 85 said way; a guide bar located to one side of said guideway; a slide mounted thereon; a finger pivoted to said slide, one end of the finger extending into the guideway above the stamp; a spring tending to draw the 90 finger into contact with the stamp; means for moving the cans through the guideway; means to move the slide upwardly; and a fixed stop contacting with and rocking the finger when the can nears its limit of up- 95 ward movement.

11. In a machine for applying stamps to cans the combination of means for presenting and applying a stamp to the lid and sides of a can; a plurality of can holders 100 having a fixed and a movable member; means for moving the holders; means for opening the movable members of the holders for the introduction of the stamped can into the same; and means for moving such 105 cans into the holders.

12. In a machine for applying stamps to cans, the combination of means for presenting and applying a stamp to the lid and sides of a can; a plurality of can-holders; 110 means for moving the same; means for opening the holders for the introduction of a can into the same; means for moving the cans into the holders; and brushes associated with said holders to bear upon the ends of 115 the stamps.

13. In a machine for stamping cans, the combination of means for positioning and wiping a stamp upon a can; a receiver for such stamped can, comprising a body member 120 having a fixed abutment, and a spring actuated jaw between which abutment and jaw the can with the stamp is clamped; and actuating means for operating said jaw.

14. In a machine for stamping cans, the combination of means for placing a stamp over the end of a can; a plurality of interconnected can receiving and clamping members, each comprising a body member having a fixed abutment at one end, a pivoted jaw 125

at the opposite end, and a spring acting to move the jaw toward the abutment; means for opening said jaws to receive a stamped can; and means for moving said can receiving and clamping members.

15. In a machine for stamping cans, the combination of means for placing a stamp over the end of a can; a plurality of interconnected can receiving and clamping members, each comprising a body member having a fixed abutment at one end, a pivoted jaw at the opposite end, and a spring acting to move the jaw toward the abutment; means for opening said jaws to receive a stamped can; means for moving said can receiving and clamping members; and means acting on the ends of the stamps as said members are moved to press the same against the sides of the cans.
20. 16. In a machine for stamping cans, the combination of means for placing a stamp over the end of a can; a plurality of interconnected can receiving and clamping members, each comprising a body element having a fixed abutment at one end, a jaw piv-

oted to the opposite end of the body; a roller carried by said jaw, and a spring serving to swing the jaw toward the fixed abutment; means for traversing said members; and means acting successively on each roller to open the associated jaw to receive a stamped can and then permitting the jaw to swing to its closed position.

30. 17. In a machine for stamping cans having hinged lids, the combination of lid closing mechanism; means for presenting the cans to said mechanism, said means and mechanism being relatively movable; and associated means for applying a stamp over the closed lid.

35. 18. In a machine for stamping cans having hinged lids, the combination of lid closing mechanism; means movable in relation thereto for presenting cans to such mechanism; and associated stamp applying means for placing a stamp over the lids of the cans after such lids are closed.

40. In testimony whereof I have signed my name to this specification.

GEORGE W. GWINN.

Copies of this patent may be obtained for five cents each, by addressing the "Commissioner of Patents, Washington, D. C."
